UNITED STATES PATENT OFFICE.

ALEXANDER PALMROS, OF COLUMBUS, OHIO, ASSIGNOR TO THE JEFFREY MANUFACTURING COMPANY, OF COLUMBUS, OHIO, A CORPORATION OF OHIO.

ELECTRIC-TROLLEY-WIRE HANGER.

SPECIFICATION forming part of Letters Patent No. 715,415, dated December 9, 1902.

Original application filed September 24, 1897, Serial No. 652,908. Divided and this application filed June 6, 1901. Serial No. 63,437. (No model.)

To all whom it may concern:

Be it known that I, ALEXANDER PALMROS, a citizen of Finland, residing at Columbus, in the county of Franklin and State of Ohio, have invented certain new and useful Improvements in Electric-Trolley-Wire Hangers, of which the following is a specification, reference being had therein to the accompanying drawings.

10 Figure 1 is a side view of a trolley-wire or conductor and supports for the same embodying my invention. Fig. 2 is a sectional view of the same on line II II, Fig. 1. Fig. 15 3 is a vertical sectional view at right angles to the section plane of Fig. 2. Fig. 4 is a plan view of one of the supporting-arms.

In this application, which is a division of my application, Serial No. 652,908, filed September 24, 1897, I have illustrated and will 20 describe a form of support for a conducting or trolley wire which I have found well adapted for use with the trolley therein shown and described, which is a more or less laterally-acting trolley, although some of the features 25 of invention are adapted as well for use with a vertically-acting trolley of the ordinary construction.

The support consists of a casting W, having one face adapted to rest against a support and provided with ears w, having apertures W' to receive fastening screws or bolts. The casting is provided with a socket two of the side walls of which are inclined inwardly from their upper to their lower edges, and 30 within this socket is arranged the expanded head W² of the hanger, having a rod W³ extending therefrom, the lower portion of the rod being provided with suitable screw-threads. The head W² of the rod W³ is separated from the casting W by insulating material Y, and the upper end of the socket in said casting is closed by a cap-plate W⁴, provided at its ends with ears w⁴, which align with and are bolted to ears w⁵ on the casting 40 W. The socket extends entirely through the casting, and, as shown at Fig. 2, the inner face of the casting is recessed around the inner open end of the socket, and the plate W⁴ lies in this recess. This construction makes 45 it possible to attach the casting with its inner

face directly against the support and at the same time to use a casting with a through-socket closed at its inner end for the insulation and the head of the hanger.

On the rod W³ below the casting W are mounted two reciprocating or engaging arms W⁶ W⁷. The arm W⁶ is provided at its inner end with a short sleeve-like portion w⁶, which extends about said rod W³ and is clamped securely between the lower face or 60 surface of the head W² by a nut W⁸. At its outer end said arm W⁶ has formed in its upper face a socket or groove 5, adapted to receive a portion of the wire V. The other arm W⁷ is provided at its inner end with a 65 sleeve w⁷, the diameter of which is somewhat greater than the diameter of the rod W³, about which it is fitted, and said sleeve W⁷ is supported by means of a nut W¹⁰. At its outer end said arm has formed in its lower surface 70 a groove or seat 6 to receive the upper portion of the wire V, and at an intermediate portion of its length said arm is provided with a lug or projection W¹¹, which extends into a socket or seat formed in a projection 75 W¹² on the other arm W⁶. Thus it will be seen that the arm W⁷ is fulcrumed to firmly grip the wire V by means of the nut W¹⁰. It will be noticed that the outer ends of the arms W⁶ W⁷ are grooved in such lines as to 80 form, with the exposed surface of the wire V, a surface over which the wheel of a trolley can freely ride.

The head W² of the hanger and the socket in which it rests are angular in cross-section 85 in order to prevent the hanger from turning in its support, which movement it is especially desirable should not take place in a hanger or support having laterally-extending wire-supporting arms and in cases where the 90 wire-engaging arms are secured to the stem of the hanger by means such as shown herein. While I prefer that the head W² should be angular, any other shape may be given thereto which will operate, in conjunction with the 95 socket in the casting, to prevent the turning of the hanger.

By the construction which I have described I secure a scissors-like trolley-wire support or hanger having two arms or parts arranged 100

to cross each other and to grasp and hold the wire by the end portions of the arms which are on one side of the crossing-line of the arms, and to have the other end portions acted 5 upon by the means which force together the wire-grasping portions of the arms. I prefer that one of the arms W^6 should be provided with an opening or passage 7, through which the other arm W^7 passes, so that the two arms 10 may both be arranged in the same longitudinal planes, and yet cross each other, as described. I also secure a trolley-arm support 15 the wire engaging and supporting arms or parts of which are easily separable to permit the ready removal and attachment of the wire and which extend laterally or at substantially right angles from the stem which sustains them.

The casting W is formed with an outwardly 20 and downwardly inclined "skirt" or rain-shed W^{14} , as shown, to shield the insulating material Y from rain or snow.

In the drawings the support is shown to be adapted to a laterally-running trolley; but 25 it is evident that the parts may be variously modified or changed in shape sufficient to enable it to be adapted to a vertically-running trolley.

The conductor-wire V is provided with 30 grip-ribs V' at the points where the supporters occur to afford means whereby the jaws of the arms W^6 W^7 may be attached to the conductor-wire without projecting over any part of the main wire, so that the presence of the 35 supporter does not in any manner interfere with the passage of the trolley-wheels. This is an important feature of my invention, as it enables me to connect the supporter firmly to the trolley-wire without obstructing any 40 of its operative portions, whereas with all forms of detachable supporters with which I am acquainted some portions of the supporters project over some portion of the operative surface of the conductor-wire, and there- 45 by offer an uneven surface to the trolley-wheel, which produces "sparking" and consequent deterioration of the wire every time the trolley-wheel passes. With my arrangement, however, the wire is as free from ob- 50 struction to the passage of the trolley-wheel at the points where the supporters are attached as at any other points. By this simple means a trolley-wire supporter is produced which may be readily attached to and 55 detached from the conductor-wire and as readily attached to and detached from the supporting-posts, walls, or other fixtures for suspending the wire.

In many localities, such as where mining and 60 excavating operations are being carried forward where frequent changes and shifting of the direction and location of the trolley-wires are required, this supporter will be found very convenient, as by the use of the removable and detachable supporters the conductor-line can be readily and quickly changed without the necessity of unsoldering any parts

or otherwise dislocating any of the fastenings. This is a great advantage and greatly enhances the value of temporary electric lines 70 to which it may be applied.

What I claim is—

1. In a trolley-wire hanger, the combination of a casting adapted to be secured to a support and provided with an interior recess angular in shape surrounded by an integral wall, a hanger having a head arranged to enter the said recess or socket, insulating material between the head of the hanger and the casting, and means carried by the hanger for securing the trolley-wire thereto, substantially as set forth. 75

2. In a trolley-wire hanger, the combination of a casting adapted to be secured to a support and provided with an interior recess angular in shape, a hanger having a head arranged to enter the said recess or socket, insulating material between the head of the hanger and the casting, and means for supporting the trolley-wire extending laterally 80 from the hanger, substantially as set forth. 85

3. In a trolley-wire hanger or support, the combination of a casting having a through-socket, a face arranged to lie flat against a support, and means by which the hanger is 90 secured to the support, a hanger having a head arranged to lie in the socket of the casting, insulating material between the head of the hanger and the casting, and means for covering the inner end of the said through-socket, 95 substantially as set forth.

4. In a trolley-wire hanger or support, the combination of a casting arranged to be secured by one face to a suitable support, the casting being provided with a socket and also 100 having that face by which it is attached to its support recessed around the said socket, a hanger having a head which is adapted to enter the said socket, insulating material between the head of the hanger and the said 105 casting, a cap arranged to close the inner end of the socket and be situated in the said recessed portion of the casting and means for securing a trolley-wire to the hanger, substantially as set forth. 115

5. In a trolley-wire hanger or support, the combination of an insulated stem, a pair of separable arms arranged to grasp and hold the wire extending laterally from the said stem, one of said arms having the lug W^{11} 120 and the other of said arms having a seat for said lug and means for holding the arms together in position to grasp the wire, substantially as set forth.

6. In a trolley-wire hanger or support, the 125 combination of an insulated stem, a pair of scissors-like arms extending laterally from the stem and arranged at one end to grasp and hold the wire, and at their other end engaging with the stem, said arms having a lever-like separable engagement between their 130 ends and means for adjusting the arms to cause them to grasp or release the wire, substantially as set forth.

7. In a trolley-wire hanger the combination of an insulated shank or stem, gripping-arms having openings in which said shank is inserted, and means adjustable on said shank transversely to the arms to engage said arms and cause the latter to grip the wire, substantially as set forth.

8. The combination in a trolley-wire hanger of two arms each having a wire-engaging jaw, said arms being detachable from each other, and means for individually adjusting said arms to cause the jaws to grasp the wire, substantially as set forth.

9. The herein-described trolley-wire support, consisting of a body W, having a stem or rod W³ projecting therefrom, two oppositely-inclined laterally-extending arms adjustably mounted on said rod and adapted to grip between their free ends a trolley-wire, and means for holding said arms stationary, substantially as set forth.

10. In a trolley-wire hanger, the combination of a body or support, an arm projecting from said body, and having in one face, near its free end, a seat or groove for a wire, another arm mounted on the body and having at an intermediate point of its length a bearing on the first said arm, and having near its free end a groove or seat for the wire, means for adjusting the inner end of the last said arm toward and from the other arm, and means for holding the first said arm stationary upon the body or supporter, substantially as set forth.

11. In a trolley-wire hanger, the combination of a body or support having a depending stem, an arm rigidly secured to said stem and extending therefrom, said arm having a wire-groove near its free end, another arm having a bearing against the said first arm at an intermediate point of its length and having its inner end loosely fitted about the said depending stem and provided near its free end with a wire groove or seat, and a nut engaging with a thread in the said supporting stem and adapted to adjust the last arm thereon, substantially as set forth.

12. In a trolley-wire hanger or support, the combination of an insulated stem, an arm ex-

tending laterally from the stem and arranged to engage with the wire, the arm being arranged to have an angular motion about the said stem, means for holding the arm rigidly after it has been angularly adjusted, and means for securing the wire to the said arm, substantially as set forth.

13. In a trolley-wire hanger or support, the combination of an insulated stem, means for holding the stem against turning, a wire-supporting arm extending laterally from the stem, and arranged to have an angular adjustment about the stem, means for securing the arm rigidly to the stem after it has been adjusted, and means for securing the wire to the arm, substantially as set forth.

14. In a trolley-wire hanger or support, the combination of an insulated stem, means for holding the stem against turning, and a scissors-like wire-support extending laterally from the stem and comprising an arm engaging at its inner end the stem and adjustable angularly about the same, means for securing the said arm rigidly to the stem after adjustment, another arm arranged to clamp the wire against the first said arm, and having a loose engagement at its inner end with the stem, and means for forcing the last said arm to clamp the wire against the other arm, substantially as set forth.

15. In a trolley-wire hanger, the combination of an insulated shank or stem, gripping-arms movable along said stem, and means adjustable along said stem transversely to said arms to engage the arms and cause them to grip the wire.

16. In a trolley-wire hanger, the combination of an insulated screw-threaded stem, gripping-arms having openings in which said stem is inserted, a nut engaging the thread of the stem for causing the gripping action of the arms, and means opposing the pressure of the nut.

In testimony whereof I affix my signature in presence of two witnesses.

ALEXANDER PALMROS.
